UNITED STATES PATENT OFFICE.

JEREMIAH P. REARDON, OF COATESVILLE, PENNSYLVANIA.

PUNCHING AND SHEARING MACHINE.

1,143,434.

Specification of Letters Patent. Patented June 15, 1915.

Application filed December 23, 1911. Serial No. 667,474.

To all whom it may concern:

Be it known that I, JEREMIAH P. REARDON, a citizen of the United States, and a resident of Coatesville, Chester county, Pennsylvania, have invented certain Improvements in 5 Punching and Shearing Machines, of which the following is a specification.

My invention relates to machines for punching and shearing metal; and the object of my invention is to provide a machine of this character for operation on metal stock for the production of corset steel or busks employed at the front of corsets; such steels or busks having or carrying the fastening devices for securing the corset to the 15 body of the wearer.

The structure forming the subject of my invention is in the form of a rotary shear with punch and die elements placed at intervals within the rotary knives and operating radially therein to properly aperture the 20 sections of metal forming the busks or steels, with strippers disposed within the dies and acting radially to expel waste pieces formed 25 in the punching operation.

These and other features of my invention are more fully described hereinafter, reference being had to the accompanying drawings, in which:

30 Figure 1, is a side elevation of a punching and shearing machine embodying my invention; Fig. 2, is a plan view of the same; Fig. 3, is a sectional elevation on the line *a—a*, Fig. 1, and Fig. 4, is a cross sectional view on the line *b—b*, Fig. 3.

The present machine is designed to be fed automatically, and the rotating punching and shearing members may carry three sets of punching and shearing elements so that 40 three steels or busks will be produced for every rotation of the same. The punches and shearing elements in themselves present no particular feature of novelty beyond their assembly in the relationship shown, so that 45 the metal fed will be simultaneously cut the proper width and punched as it is fed forward.

Automatic feeding means are provided, which may be carried at the front of the 50 machine, and it will be understood that the metal operated upon may be fed from a roll, or may be in the form of strips sufficiently long to produce three finished steels.

The punches are carried by the upper rotatable element in fixed relation with respect thereto, and comprise radially disposed

pieces of metal of proper character suitably backed, so that proper pressure can be applied axially to the operating point. The lower structure, carrying the dies against which the punches act, is provided with 60 ejector plungers in said dies; such members being disposed radially in the rotatable element and controlled by a cam which causes the plungers to protrude when they are in 65 their lowered position in order to eject punched material from the dies.

My improved machine comprises suitable frames or housings 1, having suitable journal bearings 2 and 3, for the reception of shafts 4 and 5, carrying the upper and lower cutting elements 6 and 7, respectively. Power from a suitable source, (not shown) 70 may be applied to the shaft 4 by means of a pinion 8 carried by a shaft 9, which pinion meshes with a gear wheel 10 carried by said shaft 4; the shafts 4 and 5 being geared together by suitable gear wheels 12 and 13 having the same pitch diameter and number of teeth, in order that the movements of said 75 cutting elements will be uniform.

Each of the cutting elements comprises a series of members; being preferably made in separate sections to facilitate assembly and ease of repair, and the several parts being secured together rigidly by bolts so as to be substantially of solid form. 80

The outer part of the lower or die element 6, indicated at 15, is slotted at 16 to receive dies 17, each having lips 18 for engagement with an annular recess 19 formed in the surface of the inner part 20 of the die element, over which fits the ring 15 with the inserted dies. Each of said dies carries a plunger 21 which is readily movable in and 90 out of the same for the purpose of expelling the material punched from the metal strips. This movement of the plunger is accomplished by means of a cam or eccentric 22 journaled on one of the bearings and arranged to engage said plungers. This eccentric or cam is provided with a series of projections or studs 23 extending radially therefrom and disposed in engagement with the die carrier 6 so as to be driven thereby. 100

The upper or punch element 7 is constructed in a manner substantially similar to the die element; there being two rings or plate members 25 and 26 arranged to embrace the punches 27, which are disposed 110 radially. The plate 26 is provided with an annular recess 28, and the punches have

5 lips 29 which hook into this recess. The hub of the upper gear wheel serves as an abutment or backing support for these punches to take the thrust during the punching operation.

10 The structure I have shown, provided with punches and dies to complete three steels for every revolution, is also provided with suitable cutting-off elements, comprising blades 30 carried by the lower element 6, and anvils 31, carried by the upper element 7.

15 During passage through the machine, the strips of metal are shaped and punched and cut into lengths which emerge from between the cutting elements as a finished product. To economize material, it is desirable to time the strips as they approach the rotating cutting elements so that an end 20 of each long strip will meet a pair of the cutting-off elements 30 and 31, and this result is accomplished automatically by the device shown to the right of the punching elements in Figs. 1 and 2.

25 The feed mechanism is driven by a pinion 35 in mesh with the gear wheel 10, and is carried by a shaft 36 which carries other pinions 37 and 38, which in turn transmit movement to pinions 39 and 40 driving feed 30 rolls 41 and 42. These gears, and their relation to the feed rolls 41 and 42, are clearly indicated in Fig. 2. The shaft 36 carries pinions 35, 37 and 38; the pinions 37 and 38 driving the lower roll 41 through pinions 39 on a shaft 43 carrying said roll, and said pinions 37 and 38 driving the upper roll 42 through the medium of intermediate pinions 44 meshing with the pinions 40; the latter being mounted on a shaft 45 carrying 40 said upper roll. The shaft 43 carrying the feed roll 41 and the pinions 39 is journaled in a lever 48, pivoted at 49 to the frame and having its opposite end forked at 50 to receive a small roller 51, shown in Fig. 2. The 45 shaft 36 carries a cam 52 directly under said lever 48, whose purpose is to lift that end of the lever and raise the roller 51. As this cam rotates, it strikes the lever once every revolution, causing said roller to rise 50 through the plate and allowing a strip of metal to pass under the same and over a bridging member 55 delivering said strip into engagement with the rotating die elements.

55 When a strip has passed from under the roller 51, the latter drops to the position shown by dotted lines, blocking the progress of the next strip until a pair of cutting-off elements 30 and 31 are ready for it just beyond the bridging member 55; thus avoiding a waste piece which would otherwise occur. When the roller 51 is raised, the lower feed roll 41 is also raised, holding the strip against the upper feed roll 42 and 60 propelling it forward, but when the roller

51 is down, the lower feed roll 41 is also down, leaving a space between said feed rolls to allow the strip to be pushed or fed between them until stopped by engagement with the said roller 51.

70 The feeding device is preferably carried by a bracket 60 which may be suitably bolted to the housing and the die-carrying frame 1 by bolts 61, as indicated. The housings 1 are also connected together by 75 suitable bolts 62, and the cap member of the upper bearing is clamped to the lower bearing by bolts 64, insuring a rigid construction.

80 The several parts forming the punch and die elements are confined together by bolts 70 and 71 respectively and directly secured to the gears 12 and 13.

I claim:

1. In a punching and cutting machine, the 85 combination of a pair of rotating elements, means for driving the same in unison, fixed radially disposed punches carried by one of said elements, fixed radially disposed dies carried by the other element, the latter having an annular recess, coacting stripping members movably mounted within said dies, an annular member eccentrically mounted within the recess of said rotating member and adapted to move said stripping members through the dies during movement of said 90 rotating elements, and means for driving said annular member on its eccentric axis with one of said rotating elements.

2. In a punching and cutting machine, the 100 combination of a rotating member having teeth and a hub, an annularly grooved plate adapted to said hub, a punch plate radially grooved also adapted to said hub, a series of punches adapted to the registering grooves of the respective plates and having lips in engagement with the annular groove of the first-named plate, said punches having their inactive ends in engagement with the hub whereby the latter forms a backing or anvil to take the thrust of the punches, means for locking said plates to said rotating member, a second rotating member mounted below the first, fixed radially disposed dies carried by said member, coacting stripping members 105 slidably mounted within said dies, an eccentrically mounted rotating member for moving said stripping members through the dies during movement of said rotating elements, and means for driving said rotating elements and the eccentrically mounted member simultaneously therewith.

110 3. In a punching and cutting machine, the combination of a feeding device comprising a table, a plurality of feed rolls, means for driving said feed rolls, a pivoted support for the same, and means for moving said support to raise said roll at 115 intervals.

120 4. In a punching and cutting machine, the 125

- combination of a feeding device comprising a table, a plurality of feed rolls, shafts upon which said feed rolls are mounted, means for driving said shafts, a positioning roll, a pivoted support for the same, and a cam carried by one of said roll shafts and turning therewith for moving said support to raise said roll at intervals.
5. In a punching and cutting machine, the combination of a feeding device comprising a table, a plurality of feed rolls mounted above and below the plane of said table, means for driving said feed rolls, shafts upon which said rolls are mounted, a positioning roll, and a pivoted support for the latter having its roll carrying end vertically movable with respect to the work, said pivoted support being operated from one of the feed rolls.
- 10 6. In a punching and cutting machine, the combination of a pair of rotating elements, means for driving the same in unison, fixed radial punches carried by one of said elements and disposed in sets, the punches of each set bearing a definite relation to each
- other, fixed radial dies carried by the other element and disposed for proper coaction with said dies, registering cutting means carried by said rotating elements and disposed between the sets of punches and dies, 30 coacting stripping members movably mounted within said dies, and means for moving said stripping members through the dies during movement of said rotating elements.
- 15 7. In a punching and cutting machine, the combination of a feeding device comprising a table, a plurality of feed rolls, shafts upon which said feed rolls are mounted, means for driving said shafts, a positioning roll, a pivoted support for the same, and a cam 40 for moving said support to raise said roll at intervals.

In testimony whereof, I have signed my name to this specification, in the presence of two subscribing witnesses.

J. P. REARDON.
